UNITED STATES PATENT OFFICE.

EDWARD B. ELLINGTON, OF CHESTER, COUNTY OF CHESTER, ENGLAND.

HYDRAULIC ELEVATOR.

SPECIFICATION forming part of Letters Patent No. 298,680, dated May 13, 1884.

Application filed July 16, 1881. (No model.) Patented in England December 9, 1880, No. 5,149, and in France April 5, 1881, No. 142,135.

To all whom it may concern:

Be it known that I, EDWARD BAYZAND ELLINGTON, a citizen of England, residing at Chester, in the county of Chester, England, have invented an Improvement in Hydraulic Lifts, (for which I have obtained a patent in Great Britain, No. 5,149, bearing date December 9, 1880,) of which the following is a specification.

10 This invention relates to improvements in hydraulic elevators or lifts; and it consists in the combination and arrangement of parts hereinafter fully described, and particularly pointed out in the claim, reference being had 15 to the accompanying drawing, in which the figure represents an elevation of a hydraulic elevator or lift embodying my invention, some of the parts thereof being in section.

The vertical lift-cylinder number 1 contains 20 the lift-plunger 2, which latter carries at its upper end the carriage or car 3, these parts being suitably constructed for the conditions required. The upper portion of the lift-cylinder connects by a pipe, 4, with the upper 25 portion of a fixed tube, 5, the ends of which are closed, except that the reduced trunk 6 of an elongated cylindrical piston, 7, works through its upper end. The piston 7 works through the lower end of a vertically-supported 30 receiver, 8, composed of a tubular cylinder closed at its upper end, said receiver connecting intermediate its ends with a branch pipe, 9, for communicating with a water-supply pipe, 10, which leads to an elevated accumulator or water-reservoir, or other source for 35 supplying water under pressure. The branch pipe 9 connects with a suitable casing, 11, having a water-discharge tube, 12, and inclosing a cock or valve, 13, which is connected to a 40 pivoted lever, 14, operated by a cable, 15, running upward through the elevator carriage or car, and the water-supply pipe 10 connects with the valve-casing, and also with the pipe 4, which connects the lift cylinder and fixed 45 tube, a valve, 16, being provided in the supply-pipe, at some suitable point between its connection, with the pipe 4 and the valve-casing.

The construction of the valve-casing and 50 the cock or valve and the manner of operating the latter are not material, and can be va-

riously modified, it only being requisite to provide some kind of a cock or valve, which can be operated so as to close the discharge-tube 12 and throw the supply-pipe 10 into communication with the branch pipe 9, leading to the receiver, or to close communication between the said supply-pipe and branch pipe and open communication between the latter and the discharge-tube 12. As three-way 60 cocks capable of effecting the above-mentioned results are well known, I do not consider it essential to illustrate any particular construction thereof.

In order to supply the required amount of 65 water to fill the tube 5, the valve 16 is opened to throw the water-supply pipe 10 into communication with pipe 4, which effects the supply of water to the tube, after which the valve 16 is closed and remains so. Other means for 70 supplying a column of water to the lift-cylinder and fixed tube could be resorted to; but that described is simple, and accomplishes the purpose in an effective manner. The column or quantity of water in the cylinder 1 75 and tube 5 never varies, but in the action of the apparatus is simply forced from the tube into the cylinder to raise the lift-plunger, and when the latter descends, such column of water passes back into the tube. When the cock 80 or valve 13 is actuated to throw the supply-pipe 10 into communication with the branch pipe 9, a column of water will be supplied to the receiver, which causes the piston 7 therein to descend, and with it the trunk 6, the latter 85 forcing the water from the tube 5 into the cylinder, thereby causing the lift-plunger 2 to rise. It will be evident that as the piston 7 descends a gradually-increasing water-column 90 acts on it in the receiver, and as such descent of the piston proportionally raises the lift-plunger, it will be obvious that the water-column, acting on the piston 7, will vary according to the greater or less protrusion of the lift-plunger from its cylinder, so that the increasing pressure on the piston, due to the increasing column of water above it, compensates the increase of weight of the lift-plunger, due to its greater protrusion from the cylinder.

If the carriage or car has been lifted in the manner hereinbefore explained, and it is de-

sired to lower the same, the valve 13 is operated to throw the branch pipe 9 into communication with the discharge-tube 12, which relieves the piston of the pressure from the 5 accumulator or other source of water-pressure supply, and the lift-plunger will at once begin its descent, causing the water in its cylinder to flow back into the tube 5 and elevating the trunk 6 and piston 7. As the piston rises 10 it displaces the column of water in the receiver, and causes it to gradually flow off through branch pipe 9 and discharge-tube 12, and hence the column of water is gradually 15 lessened as the protrusion of the lift-plunger from its cylinder becomes less, thus counterbalancing the plunger and its carriage or car.

The discharge-tube 12 will in practice lead to a sewer or some other place for carrying off the discharge-water, and the piston and its 20 trunk, as well as the lift-plunger, will work accurately in stuffing-boxes, which provide tight joints for the parts.

By my invention it is impossible for the carriage or car to fall suddenly, and thus endanger life, and I provide simple but efficient 25 means whereby the invariable weight of the lift-plunger and car, as well as the variable weight thereof resulting from a greater or less protrusion of the lift-plunger from the cylinder, is compensated without the use of weights, 30 chains, and pulleys.

Having thus described my invention and

the best means I know of carrying it out in practice, I hereby declare that I make no general claim to counterbalancing the plunger 35 and car of a hydraulic lift by hydraulic pressure in substitution for weights with their chains and pulleys; nor do I claim interposing between the lift-cylinder and the source of pressure an intermediate cylinder or cylinders with 40 pistons or plungers so arranged and operating that the same liquid is made to flow to and from the lift-cylinder without supply from the source of pressure or discharge to the drain or escape; but

45

I claim—

The combination of a vertical water-tube, a receiver, and a differential piston interposed between the cylinder of a hydraulic lift and the source of water-supply, whereby the column of water acting on the said piston increases proportionally to the protrusion of the plunger from the lift-cylinder, substantially as described.

50

In testimony whereof I have signed my name 55 to this specification, in the presence of two subscribing witnesses, this 30th day of June, A. D. 1881.

E. B. ELLINGTON.
